UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REVERSAL AND CONTROL OF REGENERATIVE FURNACES.

Application filed February 15, 1923. Serial No. 619,185.

The present invention relates to the reversal and control of regenerative furnaces, particularly those using hot producer gas for fuel. The invention utilizes, in part, the principles of operation which characterize the apparatus shown and described in my United States Letters Patent No. 1,464,002, dated August 7, 1923, all as more fully hereinafter described with reference to the accompanying drawings, wherein—

Fig. 1 is a diagrammatic plan view of the invention as applied to a regenerative furnace using producer gas as fuel.

Fig. 2 is a sectional view showing one of the air regenerators of the furnace with its associated parts.

Fig. 3 is a sectional view of drafting devices associated with each air regenerator of the furnace, and also with a waste heat boiler.

Like reference characters refer to like parts in the different figures.

Referring to Fig. 1, the heating chamber 1 of the furnace is in communication, at opposite ends, with air regenerators 2, 2' and gas regenerators 3, 3', the last named being connected by means of flues 4 and 4', respectively, with a gas reversing valve 5 of any well known type,—here shown, by way of example, as of the rotary or oscillatory type. Said valve in the position illustrated is adapted to direct hot producer gas, from a supply conduit 6, into the passage 4' and thence to the furnace by way of regenerator 3'; at the same time, serving to connect the exhaust side of the furnace, by way of gas regenerator 3 and passage 4 with a waste heat boiler 7. When the valve 5 is reversed, the flow of fresh hot gas to the furnace is by way of passage 4 and regenerator 3, while the products of combustion at the same time pass through regenerator 3' and passage 4' to the waste heat boiler.

The air regenerators 2, 2' provide, adjacent the furnace, the usual brick checker work 8, and preferably, in addition thereto, said regenerators have extensions 9, 9' providing metallic checker work 10, as

shown in Fig. 2. Each extension 9, 9', and 50 also the exit passage 11 from waste heat boiler 7, communicates with an open-ended duct 12, having a suitable contracted throat portion 13 wherein is disposed a fan or blower of the type, for instance, shown at 55 14 in Fig. 3. Each of the three fans or blowers 14 is driven independently by means of a reversible, independently controlled, actuating device, as, for instance, a steam turbine 15, or a reversible electric motor, such as shown in the aforesaid copending application.

In the present instance, each fan or blower 14 is carried on the end of a shaft 16, the latter constituting an extension of the driving turbine shaft, and being journaled in a bearing 17 provided by a removable supporting member 18. As shown in Fig. 3, the entire structure, as above described, is insertible, as a unit, from the outside, 70 through a suitable opening provided by the enlargement 19 which connects each passage 9, 9' and 11 with its associated duct 12; in this way, the removal of any one or all of these blowing devices, for purposes of 75 repair or replacement, is greatly facilitated, with a minimum loss of time occasioned by the necessity for such replacement. In fact, either of the two blowing devices associated with the air regenerators may be removed and replaced, or repaired, without shutting down the furnace, when such removal takes place during the intake phase of the blower's operation. As also shown in Fig. 3, the bearings 17 for each fan or blower, being exteriorly located, are not subject to overheating; furthermore, if desired, said bearings may be additionally cooled by the use of a fan 20 carried by shaft 16 on the outside.

In connection with the passage of gases through the furnace from right to left, as shown by the arrows in Fig. 1, the turbine 15, associated with regenerator passage 9', causes its fan or blower 14 to draw in the 95 air through the open upper end of associated duct 12, while the other air regenerator turbine, associated with passage 9, runs in the

opposite direction, to cause its fan or blower 14 to draw waste gases from the furnace for expulsion from the upper end of left hand duct 12. The reversal of the furnace is effected by simply reversing both the right and the left hand turbines 15, 15, and also the valve 5, it being understood that with either direction of flow through the furnace, the third or intermediate duct 12, associated with waste heat boiler 7, is invariably employed for outflow or exhaust. However, the turbine driven fan associated with this third or intermediate duct 12 is preferably reversible, to permit of intake 15 operation, at a slow speed, during a stand-over of the furnace, when the gas supply thereto is shut off, as by a damper 21; this assists in holding the heat in the furnace pending the resumption of gas supply there- 20 to.

With such a system as above described, relying wholly upon forced draft, there is no need for the retention of the usual high temperatures in the waste products, such as 25 is relied upon to produce stack draft. Consequently, in the air regenerators of the system, the usual brick checker work 8 is supplemented by the metallic checker work 10, in order to absorb from the outgoing gases 30 as much as possible of the heat, that in ordinary systems is purposely retained for the production of stack draft. In this connection, the use of metal checker work in these secondary regenerators 9 and 9' is prefer- 35 able to brick, since metal has a natural tendency to readily pick up and give off heat at comparatively low temperatures.

In the gas regenerator passages however, this secondary regeneration is not availed 40 of, since the producer gas from conduit 6 is already at a temperature of approximately 1200° Fahrenheit, and consequently, the usual regenerators 3 and 3' are sufficient. Instead, the low temperature heat 45 contained in the waste products leaving by way of valve 5 is utilized in the boiler 7 for the generation of steam, with which to drive the three turbines 15, 15, 15.

It is to be noted that the apparatus affords positive control over both the ingoing and outgoing gases, owing to the fact that the mechanical drafting devices used for both ingoing and outgoing gases are susceptible of any manipulation or variation 55 that may be desired. In other words, the separate and independent control and operation of the turbines or motors of the three fans or blowers 14, 14, 14 gives to the apparatus, wholly apart from the use of any dampers or valves, the widest possible 60 latitude and flexibility in meeting all of the various conditions of furnace operation. For instance, under normal conditions of operation, the fan or blower on the outgoing 65 side of the furnace must be able to handle a

greater volume of gases than the blower on the ingoing side, due to the increase of volume under high temperature; this is made possible by the independent control of said fans or blowers, which permits one 70 to be operated at a higher speed than the other. Again, the atmospheric conditions may at times be such as to require very little mechanical assistance in drafting the furnace; at such times, either one or both of 75 the fans or blowers may be slowed down, or may be rendered inoperative.

To cool the furnace proper for purposes of repair, all three fans or blowers 14, 14, 14 are operated in the discharge direction, 80 to draw out all gaseous products through the air regenerator passages and through the waste heat boiler; the present invention permits of this cooling in much less time than that required when the usual types of reversing apparatus are employed.

Under all circumstances, the volume of the products of combustion drawn through the waste heat boiler may be governed by the speed of the associated fan or blower 14 and, 90 in this way, the required amount of steam may be generated, and the proper temperatures maintained in the gas regenerators 3, 3'. It will be noted further, in connection with the use of this waste heat boiler, that 95 the fresh gas and air supplied to the furnace are kept entirely separate, one from the other, at all times and in all places, except where they are united in the furnace. Therefore, all danger of explosion by contact of 100 fresh gas and air in the waste heat boiler is avoided, which is not the case where waste heat boilers are used under existing conditions. That is to say, with the ordinary use of waste heat boilers, and also with the ordinary disposal of all combustion products through a single stack, each reversal of a 105 regenerative furnace creates the possibility of an explosion, because there is invariably the merging into a single current, of the fresh gas and the fresh air which is trapped each time in the respective gas and air regenerator passages. In the present construction however, the trapped fresh gas is exhausted independently of and apart from the 110 trapped fresh air, and consequently no explosive or combustible mixture is ever formed outside of the furnace.

I claim,

1. Reversing apparatus for a gas fired regenerative furnace, comprising a valve associated with the gas regenerator passages of the furnace, for reversing the gas supply, in combination with independently reversible blowing devices associated, respectively, with each of the air regenerator passages of said furnace.

2. Reversing apparatus for a gas fired regenerative furnace, comprising a valve associated with the gas regenerator passages of

the furnace, for reversing the gas supply, in combination with independently reversible blowing devices associated, respectively, with each of the air regenerator passages of said furnace, and a third independent blowing device associated with said gas reversing valve to exhaust the products of combustion delivered therethrough.

3. Reversing apparatus for a gas fired regenerative furnace, comprising a valve associated with the gas regenerator passages of the furnace, for reversing the gas supply, in combination with independently reversible blowing devices associated, respectively, with each of the air regenerator passages of said furnace, a waste heat boiler for the passage of products of combustion delivered through said gas reversing valve, and a third independent blowing device associated with said waste heat boiler.

4. Reversing apparatus for a gas fired regenerative furnace, comprising a valve associated with the gas regenerator passages of the furnace, for reversing the gas supply, in combination with independently reversible blowing devices associated, respectively, with each of the air regenerator passages of said furnace, the latter comprising primary and secondary checker work chambers.

30 5. The combination with a gas fired regenerative furnace, of a waste heat boiler to receive the products of combustion issuing selectively from each of the gas regenerator passages of said furnace, and means independent of said waste heat boiler, and isolated therefrom, for supplying air to said furnace.

40 6. The herein described method of utilizing a portion of the exhaust gases of a regenerative furnace in a waste heat boiler, which consists in segregating for use in said boiler the gases discharged through the gas regenerator passages of said furnace, and maintaining the supply of air to said furnace through passages isolated from said waste heat boiler.

50 7. In a gas fired regenerative furnace, a reversible blowing device associated with each air regenerator passage, in combination with a third blowing device common to both gas regenerator passages.

55 8. In a gas fired regenerative furnace, a reversible blowing device associated with each air regenerator passage, in combination with a third blowing device common to both gas regenerator passages, and means selectively operable on said first mentioned blowing devices for causing them either to exhaust gases from both ends of the furnace simultaneously, or to supply air to both of said ends simultaneously.

60 9. In a gas fired regenerative furnace, a reversible blowing device associated with each air regenerator passage, in combination with a third blowing device common to both

gas regenerator passages, and means selectively operable on said first mentioned blowing devices for causing them either to exhaust gases from both ends of the furnace simultaneously, or to supply air to one end while exhausting gases from the other end.

10. In a gas fired regenerative furnace, a reversible blowing device associated with each air regenerator passage, in combination with a third blowing device common to both gas regenerator passages, and means selectively operable on said first mentioned blowing devices for causing them to supply air to both ends of the furnace simultaneously, or to supply air to one end while exhausting gases from the other end.

11. In apparatus of the class described, the combination with a conduit adapted for the flow of hot gases, of a fan disposed therein to procure movement of gases through said conduit, said fan and its bearings being carried by a member insertible in said conduit as a unit, from the outside, to permit the removal and replacement of said fan without dismantling the conduit.

12. The combination with a gas fired regenerative furnace, of a waste heat boiler adapted to be heated by combustion products issuing from said furnace, means for connecting said waste heat boiler, alternately, at each reversal of the furnace, with one or the other of the gas regenerator passages of said furnace, and drafting means isolated from said waste heat boiler for withdrawing combustion products alternately from one or the other of the air regenerator passages of the furnace, thereby to prevent admixture, in said waste heat boiler, of fresh air and fresh gas trapped in the respective air and gas passages when the furnace is reversed.

13. The combination with a gas fired regenerative furnace, of drafting means for the disposal of combustion products exhausted alternately at each reversal of the furnace from one or the other of the gas regenerator passages of said furnace, and other drafting means, independent of said first mentioned drafting means for withdrawing combustion products alternately from one or the other of the air regenerator passages of the furnace, thereby to prevent admixture, in a single drafting means, of fresh gas and fresh air trapped in the respective air and gas passages when the furnace is reversed.

14. The combination with a gas fired regenerative furnace, of a waste heat boiler adapted to be heated by combustion products issuing from said furnace, means for connecting said waste heat boiler, alternately, at each reversal of the furnace, with one or the other of the gas regenerator passages of said furnace, and drafting means isolated from said waste heat boiler for withdrawing combustion products alternately

ly from one or the other of the air regenerator passages of the furnace, thereby to prevent admixture, in said waste heat boiler, of fresh air and fresh gas trapped in the respective air and gas passages when the furnace is reversed, each of said air regenerator passages comprising a primary refractory

checkerwork chamber and a communicating secondary metallic checkerwork chamber, the latter for extracting heat from said combustion products at approximately the temperatures utilized in said waste heat boiler.

Dated this ninth day of February, 1923.

GEORGE H. ISLEY.
